United States Patent Office

Des. 185,050
Patented Apr. 28, 1959

185,050

REFUSE RECEPTACLE FOR CIGARETTES OR THE LIKE

Arthur H. Swanson, Peoria, and Claude S. Humphrey,
Moline, Ill., assignors to Standard Industrial Products
Co., a corporation of Illinois

Application February 11, 1958, Serial No. 49,587

Term of patent 14 years

(Cl. D58—17)

The rear not shown is substantially flat and plain.

We claim:

The ornamental design for a refuse receptacle for cigarettes or the like, as shown and described.
